UNITED STATES PATENT OFFICE.

ALMON D. SIEWERT, OF PASADENA, CALIFORNIA.

LIGATURE-DISPENSING CAP.

Application filed July 29, 1925. Serial No. 46,721.

This invention relates to improvements in ligature dispensing devices, and more particularly to a cap for tubes containing tooth paste, and serving as a dispenser for an especially prepared thread or yarn commonly known as dental floss and used for removing food particles from between the teeth.

The object of the invention is to provide a convenient means for dispensing the ligature, by utilizing a container which also serves as the cap of a tube of dentifrice, thereby incorporating the requirements for complete tooth cleansing in a single commodity with the attendant advantage or benefit of promoting their more general use.

The novel features of the invention are disclosed in the accompanying drawings, in which—

20 Figure 1 is a view in elevation of an ordinary tube of tooth paste with the cap applied;

Figure 2 is an enlarged detail view of the cap in cross section; and

25 Figure 3 is an end view of the cap.

The cap as preferably designed, is a hollow conical shaped body, of a metal suitable for the purpose, its external conformation varying according to the degree of ornamentation desired.

In general, the cap consists of an internally threaded base portion 1 which screws onto the threaded neck *a* of the tube A containing tooth paste or other tooth cleansing preparation. Above the base portion is a hollow receptacle 2, the walls thereof converging to an apex and forming a cavity in which a spool 3 of the ligature is enclosed. At the apex of the receptacle is a small opening 4 through which the free end of the ligature is threaded to be withdrawn in such lengths as needed.

The spool 3 preferably consists of a circular base plate 5, in which is mounted a spindle 6 on which the ligature is tightly and compactly wound, and in such a manner that it will unwind freely as it is drawn through the opening.

The preferable method of constructing

and assembling the cap is to make the spindle with its base plate separate from the body of the cap, and having wound the ligature on the spindle, to insert the spool assembly upwardly through the opening at the base of the cap, the plate 5 seating against a shoulder at the base of the threaded socket which forms the closure for the tube A. The metal being relatively soft, the plate is readily wedged in place and the cap is complete.

These caps may be either sold as a part of the tube or separately to be substituted for the ordinary tube cap, this being a matter of choice. It is contemplated that approximately five yards of ligature can be wound onto the spool and thus afford an ample supply. As an added convenience, a notch 7 with sharpened edges is formed on the outer surface of the cap so that the ligature can be severed as it is used.

I claim as my invention:

1. The combination with collapsible tube for dentrifrice, having a threaded neck portion surrounding the opening to said tube, of a cap comprising a threaded portion 75 forming a closure for said tube and a substantially conical hollow body portion surrounding said base portion and provided with an opening in its apex, a spindle mounted in said body member and a length of ligature wound on said spindle and having its free end extending through the opening in said body.

2. The combination with a collapsible tube having a threaded discharge neck of a cap comprising a hollow body having a threaded portion at one end, and a small opening at its opposite end, a plate fixed transversely of said body and forming a cap portion and separate dispensing cavity, a spindle fixed to said plate and extending into said cavity, a length of ligature wound on said spindle with its free end passing through said opening.

Signed at Pasadena this 23rd day of July, 1925.

ALMON D. SIEWERT.
